Primary Examiner — Karen E Kearney*Assistant Examiner* — John M Otte(74) *Attorney, Agent, or Firm* — Design IP(57) **CLAIM**

The ornamental design for a display screen or portion thereof with graphical user interface, as shown and described.

DESCRIPTION

FIG. 1 is a front view of a first embodiment of a display screen or portion thereof with graphical user interface showing our new design;

FIG. 2 is a front view of a second embodiment of a display screen or portion thereof with graphical user interface showing our new design; and,

FIG. 3 is a front view of a third embodiment of a display screen or portion thereof with graphical user interface showing our new design.

The broken line showing in FIGS. 1-3 of a portion of a display screen forms no part of the claimed design. The broken line showing in FIGS. 1-3 of text and portions of the graphical user interface represents environmental subject matter and forms no part of the claimed design. All text is shown in broken lines.

1 Claim, 3 Drawing Sheets(56)
